WORK ILLUMINATING TOOL

Glen E. Montgomery, Oakland, Calif.

Application March 1, 1940, Serial No. 321,675

1 Claim. (Cl. 240—6.46)

This invention relates to a work-illuminating tool and has for its principal object the provision of a tool handle for supporting screw driver bits, socket wrenches, and other tools, in which will be incorporated an electrical illuminating means which will project a beam of light upon the work upon which the tool is being used.

Other objects of the invention are to provide a device of this character in which all metallic opaque arms and similar structures will be eliminated from the path of the light beam so that no shadows will be thrown and to so construct the device that the tool holding portion thereof will simultaneously serve as a lens.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

Fig. 1 is a perspective view illustrating the improved tool handle with a screw driver bit in place therein.

Fig. 2 is an enlarged perspective view of the tool with the screw driving bit inserted therein.

Fig. 3 is a perspective view of a screw driver bit which may be employed with the tool.

Fig. 4 is an enlarged longitudinal section through the tool handle.

Fig. 5 is a front end view thereof.

Fig. 6 is a perspective view illustrating the switch plug employed in the handle.

Fig. 7 is a detail perspective view of the switch plug locking ring.

The illuminating handle may be used with any suitable tool. It is illustrated for use with a screw driver bit, shown at 10, having a square shank 11 and screw bit extremity 12. The handle comprises a hollow outer tube 13 of any desired material preferably of "Bakelite" or similar hard plastic material. One extremity of the tube 13 is plugged by means of a relatively thick plug of transparent plastic 14, such as "Lumarith" or similar material.

The transparent plug is moulded or otherwise formed about an imbedded metal ferrule 15. The ferrule is non-circular in shape to prevent rotation of the tool therein, and is preferably square to receive the square shank 11 of the screw driver bit 10. The inner face of the plug is formed with

a concavity 16 into which a small, lens-type, electric lamp 17 projects.

The lamp is threaded or forced into a receiving socket 18 on a metallic, bellied battery cap 19. The battery cap fits snugly over the foremost cell of a series of dry cell batteries 20 which are slipped into the hollow interior of the tubular handle 13. The batteries are held in place by means of a rotatable switch disc 21 which is retained in place in the rearward extremities of the handle tube by means of an expanding wire ring 22.

The interior face of the disc 21 is provided with a metallic cross strip 23 to which is secured a coiled compression spring 24. The spring 24 acts against the bottom of the rearmost cell and forces all of the cells forwardly to press the lamp 17 into its receiving concavity 16. A metallic conductor strip 25 extends longitudinally of the inner wall of the tube 13 and makes electrical contact at its forward extremity with the battery cap 19 and at its rearward extremity with the cross strip 23.

Thus, as the disc 21 is rotated, and it is provided with a finger handle 26 by means of which it may be rotated, the cross strip can be brought into contact with the conductor strip 25 to close the circuit to the lamp.

It will be noted that the entire forward end of the handle member is transparent. There are no opaque cross braces or other structure so that no shadows are thrown into the light beam to interfere with clear illumination of the area about the screw, as shown in Fig. 1.

The screw driver bit is provided with a shoulder 27 which limits the amount of the insertion in the ferrule 15. For extra heavy work, the transparent plug 14 may be keyed to the outer cylinder 13 by means of a suitable locking key 28.

While a specific form of the improvement has been described and illustrated herein, it is desired to be understood that the same may be varied, within the scope of the appended claim, without departing from the spirit of the invention.

Having thus described the invention, what is claimed and desired secured by Letters Patent is:

A work illuminating tool comprising: a hollow outer tube; a relatively long plug of transparent plastic fixedly imbedded in the forward extremity of said tube; a hollow, square ferrule permanently imbedded in a socket in the outer face of said plug; a concave socket in the inner face of said plug directly behind said ferrule; a series of dry cells in alignment in said tube; a

2,242,536

2
battery cap fitted snugly over the foremost cell; an electric globe threaded into said cap with its tip enclosed in the concave socket of said plug; a rotatable switch disc in the rearward extremity of said tube in circuit between said cells and said globe; a spring on said disc for forcing said

cells forwardly to maintain the globe in its concavity; an expanding wire ring for holding said disc in place; and a finger grip on the external face of said disc to facilitate its rotation for switching purposes.

5 GLEN E. MONTGOMERY.
